(57) **CLAIM**

The ornamental design for a wireless microphone set, as shown and described.

DESCRIPTION

FIG. 1 is a front perspective view of a wireless microphone set, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of an enclosed portion of the wireless microphone set labeled 9 in FIG. 1.

The evenly-dashed broken lines in the drawings illustrate portions of the wireless microphone set that form no part of the claimed design. The dash-dot broken lines in the drawings enclosing portions of the wireless microphone set illustrated in enlargements form no part of the claimed design.

1 Claim, 9 Drawing Sheets
